UNITED STATES PATENT OFFICE.

HENRY N. QUALEY, OF VERMILION, SOUTH DAKOTA.

DESIGN FOR AN INCANDESCENT-LAMP HANGER.

SPECIFICATION forming part of Design No. 30,942, dated June 6, 1899.

Application filed July 2, 1898. Serial No. 685,060. Term of patent 14 years.

To all whom it may concern:

Be it known that I, HENRY N. QUALEY, a citizen of the United States, residing at Vermilion, in the county of Clay and State of South Dakota, have invented and produced a new and original Design for a Hanger for Incandescent Lights, of which the following is a specification, reference being had to the accompanying drawing, forming part thereof, and in which I have shown a perspective view illustrating a hanger for incandescent lights, showing my new design.

The essential feature of my design consists in the peculiar shape and design of the block A, which is shaped in such a manner as to provide the cylindrical portion E and tapering or

essentially conical portion F, terminating in a ball G, a slide-shoulder F' being designed adjacent to said ball. Between the cylindrical portion E and conical portion F are the 20 circumferential ribs H and I, and between the said ribs I design a series of protuberances J, hemispherical in shape.

Having thus fully described my invention, what I claim as new, and desire to secure by 25 Letters Patent, is—

The design for an incandescent - lamp hanger, substantially as shown and described.

HENRY N. QUALEY.
